UNITED STATES PATENT OFFICE

EDWARD S. BECKWITH, OF ALBION, NEBRASKA

ROPE HALTER

Application filed November 13, 1928. Serial No. 319,160.

My invention relates to rope halters, the present embodiment being an improvement on the rope halter which I have shown and described in my prior application, Serial No. 5 273,398, filed April 27, 1928.

The primary object of the present invention is the provision of an adjustable halter having no loose and flapping ends regardless of the adjustment.

10 A second object of the invention is the provision of metal wearing surfaces for the purpose of increasing the life of the halter.

Having in view these objects and others which will be pointed out in the following 15 description, I will now refer to the drawings, in which

Figure 1 is a view showing the adjustable connection of the halter parts on the left-hand side of the horse's head.

20 Figure 2 is an illustration of a portion of the halter showing the adjustment of the crown piece.

Figure 3 is a view similar to Figure 2 but showing how the adjustment may be made.

25 Figures 4 and 4A illustrate the fixed clamps which are used for uniting the parallel portions of the rope in the crown piece and which are used in adjusting the halter to heads of various sizes, the clamps having 30 metal wearing surfaces.

The present invention relates to the connection between the crown piece 19 and the loop formed by the chin piece and throat latch of the halter at one side of the horse's head. 35 This feature is shown in Figure 1 and more specifically in Figures 2 and 3, one of the details being best shown in Figure 4A. As shown in Figure 1, the crown piece consists of a portion of rope which is doubled upon it- 40 self to form a loop. The chin piece 13 and the portion 15 of the throat latch are integral forming the loop 14, the parallel portions of the rope being secured together by means of any suitable clamp such as that shown at 45 in Figures 2 and 3.

The hook member 29 is secured in the loop 14 as best shown in Figures 2 and 3. This hook is provided with a ring 29^a and with two hook portions 29^b and 29^c. The ring 29^a 50 is adapted to surround the loop 18 as shown

in Figure 2 and the hook 29^b is adapted to engage the loop 18.

The parallel portions of the crown piece 19 are united by clamps 25 and 26 which are identical in form. Any desired number of 55 these clamps may be employed and I have shown only two of these clamps merely for purposes of illustration. The essential feature in the present invention is that the clamp 25 be spaced from the end of the member 18 a 60 distance which is substantially equal to the distances between the hook members 29^b and 29^c. It is also necessary that the clamp 26 be spaced from the clamp 25 at substantially 65 the same distance.

The purpose of this construction will be apparent from an inspection of Figure 3. The halter may be adjusted by drawing the crown piece 19 through the ring 29 and by latching it in any desired position. When 70 the crown piece is drawn far enough for the hook 29^c to engage the loop 18, the hook 29^b will engage the clamp 25 as shown in Figure 3. At the next adjustment the hook 29^c would 75 engage the clamp 25 and the hook 29^b would engage the clamp 26. It will therefore be apparent that regardless of the position of the adjustment, the halter presents no flapping end. Not only are flapping ends avoided, but 80 a double holding means is provided in all cases except when the halter is used for the largest animals.

In order to provide a metal wearing surface between the hooks 29^b and 29^c and the clamps 25 and 26, I provide tongues 28 as 85 shown in Figure 4A which are turned over between the parallel strands of the rope. As a result, the hook members will bear against the tongues 28 which do not readily chafe as the rope would during use.

Having thus described my invention in such full, clear, and exact terms that its construction and operation will be readily understood by others skilled in the art to which it pertains, what I claim as new and desire to 95 secure by Letters Patent of the United States is:

1. A halter having a crown piece consisting of a pair of parallel strands of rope with a loop at the extremity thereof, a plurality 100

of clamps uniting said strands of rope, said clamps being spaced equidistantly from each other and the outermost of said clamps being spaced a like distance from the extremity of said crown piece, said halter also having a loop at the junction of the throat latch and one of the cheek pieces of said halter, and a hook member secured to said last named loop and adapted to simultaneously engage 10 said first mentioned loop and one of said clamps or to simultaneously engage two of said clamps.

2. A halter having a crown piece consisting of a pair of parallel strands of rope with 15 a loop at the extremity thereof, a plurality of clamps uniting said strands of rope, said clamps being spaced equidistantly from each other and the outermost of said clamps being spaced a like distance from the extremity 20 of said crown piece, said halter also having a loop at the junction of the throat latch and one of the cheek pieces of said halter, and a hook member secured to said last named loop and adapted to simultaneously engage said 25 first mentioned loop and one of said clamps or to simultaneously engage two of said clamps, said hook member having two hooks projecting therefrom and spaced apart a distance equal to the distance between two of said 30 clamps.

3. A halter having a crown piece consisting of a pair of parallel strands of rope with a loop at the extremity thereof, a plurality 35 of clamps uniting said strands of rope, said clamps being spaced equidistantly from each other and the outermost of said clamps being spaced a like distance from the extremity of said crown piece, said halter also having a loop at the junction of the throat latch and 40 one of the cheek pieces of said halter, and a hook member secured to said last named loop and adapted to simultaneously engage said first mentioned loop and one of said clamps or to simultaneously engage two of said 45 clamps, said clamps being provided with in-turned tongues between the strands of rope to provide wearing surfaces for said hook member.

50 In testimony whereof I affix my signature.
EDWARD S. BECKWITH.
